FIELD SWITCH

Walter Haines Schymik, Oreland, Pa., assignor to
 I-T-E Circuit Breaker Company, Philadelphia,
 Pa., a corporation of Pennsylvania

Application June 2, 1942, Serial No. 445,429

4 Claims. (Cl. 175—298)

1

My invention relates to a field switch for placing a resistance across the field winding of a motor or other similar inductive circuit when the circuit is opened and, more particularly, to a combined circuit breaker and field switch so arranged that they operate to complement each other.

During the interruption of highly inductive direct current circuits, momentary high voltages are produced, as is well known in the art, which may be sufficient to break down the motor winding and other insulations of the system. To prevent damage to the winding, it is customary to provide a bypass circuit around the winding through a resistance during the opening of the supply circuit. This resistance in the circuit reduces the momentary voltage rise in the circuit and, therefore, protects the winding of, for instance, the motor or similar inductive circuit.

In circuits of this character, it is thus necessary immediately to introduce a resistance when the motor circuit is interrupted for any reason.

An object of the present invention is to provide means for integrating a circuit breaker and field switch (for connecting the field winding across a resistance) in such manner that the two elements operate to complement each other, so that one is opened when the other is closed.

Another object of the present invention is to mount the field switch operating elements on the same panel with the circuit breaker operating elements so that they may be simultaneously placed in position.

A further object of the present invention is to mechanically interlock circuit breaker and field switch operating elements so that operation of the circuit breaker results in operation of the field switch.

Still another object is the arrangement of the circuit breaker and field switch operating members so that the field switch closes before the circuit breaker opens and so that it opens after the circuit breaker closes.

Where circuit breakers are mounted on trucks which are to be racked into and out of engagement with cells in a stationary switchboard, additional means should be provided for placing a resistance across the field winding of a motor or other similar inductive circuit so that an momentarily induced voltage will not result in damage.

Accordingly, a further object of the present invention is the provision of means for mounting a field switch and circuit breaker elements on a removable circuit breaker truck in such man-

2

ner that when the truck is racked into position, both the field switch elements and the circuit breaker elements are simultaneously placed in condition for operation.

Another object of my invention is the arrangement of field switch and circuit breaker elements on a removable truck in such manner that a resistance is always connected across the field winding or similar inductive circuit when the circuit breaker is racked out of position.

Still another object is to provide a cell having a switch independent of the disconnecting contacts and which is operated to open and closed position by the racking in and out of the truck.

These and many other objects of my invention will be apparent and, where not apparent, pointed out in the following description and drawings, in which:

Figure 1 is a side elevation with one of the side sheets removed of a circuit breaker truck withdrawn from a stationary switchboard cell.

Figure 2 is a front view of a circuit breaker panel showing the contacts and a portion of the mechanism thereof and the field switch.

Figure 3 is a side view taken from line 3—3 of Figure 2 looking in the direction of the arrows, showing the circuit breaker panel carrying the circuit breaker and field switch elements in its operative position in the switchboard cell.

Figures 4, 5 and 6 are schematic views showing three operating positions of the elements of Figures 1, 2 and 3; Figure 4 showing the circuit breaker closed and field switch open; Figure 5 showing the circuit breaker open and field switch closed; and Figure 6 showing the circuit breaker and field switch operating elements racked out of the switchboard cell with an auxiliary field switch in closed position.

Figure 7 is a schematic view illustrating the operation of the field switch.

Figure 8 is a cross-sectional view corresponding to a portion of Figure 3 and showing a modified form of disconnect structure for my field switch.

In general, my invention contemplates inserting a resistance 85 (Figure 4) across an inductive winding 40 in response to any action which disconnects such a winding from its source of supply and just preceding such disconnection; and for cutting said resistance out of the circuit with the inductive winding immediately after said winding has been connected with its source of supply.

This action is extended to include not only operations where the inductive winding may be dis-

connected by manual or automatic switching equipment but to operations where the inductive winding is disconnected by disengagement of disconnect contacts through the operation of a truck carrying a circuit breaker in which case the resistance 85 is connected in circuit with the inductive winding 40 on the removal of the truck.

My invention also contemplates a cell having a switch thereon and a truck which when racked into the cell disconnects the switch. In my specific embodiment, the switch normally maintains the resistance 85 across the inductance 40 and is operated to open this contact when the truck is racked into the cell.

Inasmuch as the main circuit breaker is always in trip position during the racking operations, the auxiliary means which is mounted on the truck for closing the resistance circuit across the inductance is in closed position prepared to replace the switch in the cell when the truck is racked in.

Referring now to Figure 4, I have here substantially shown a circuit breaker truck 10 racked into position in engagement with the elements of a switchboard cell structure 20. The showing of Figure 4 is entirely schematic and the actual form and exact operation of each of the elements therein shown will hereinafter be explained in connection with the description of Figures 1 to 3.

The circuit breaker and field switch operating elements are mounted on a panel 11 of insulating material. The circuit breaker 13 comprises a contact carrying arm 14 pivoted at 15 and carrying the contact bridging element 16. The bridging contact 16 may be moved to closed contact position by the operating arm 17 which rotates about its pivot 18 and is in toggle relation with the link 19. The circuit breaker is held in closed circuit position by the latch 23. When the latch 23 is disengaged from the operating arm 17 in any suitable manner as, for instance, by the usual tripping coil (not shown) or by manual operation, the toggle 17-19 is permitted to break downwardly to the position shown in Figure 5, thus permitting circuit breaker contact 16 to move to the left (with respect to Figures 4 and 5) and thereby disengaging the movable contact 16 from the stationary contacts 30 and 31.

The stationary contacts 20 and 31 are mounted on the front of the panel 11 and are secured to back connection studs 32 and 33 which respectively terminate in disconnect contact elements 35 and 36. These disconnect contact elements 35 and 36 of the circuit breaker engage respectively with the stationary disconnect contacts 37 and 38 in the switchboard cell 20 when the circuit breaker is racked into position.

Accordingly, when the circuit breaker is in position and the movable contact 16 thereof is in engagement with its stationary contacts 30 and 31, current for the winding 40 of the motor or dynamo 41, extending from a source of supply over conductor 9, passes through the disconnect contacts 37 and 35, back connection stud 32, the stationary circuit breaker contact 30, the movable bridging contact 16, the stationary contact 31, the back connection stud 33 and the disconnect contacts 36 and 38 to the opposite terminal 8 of the source of supply.

Obviously, therefore, when the movable circuit breaker contact 16 is moved to its tripped or open position, as shown in Figure 5, the circuit through the field winding 40 of the dynamo or motor 41 is broken. Also, as shown in Fig-

ures 4 and 5, when the movable contact 16 of the circuit breaker 13 is moved to open position, the movable contact 50 of the field switch 51 is moved to closed circuit position.

5 The field switch 51 comprises an upper stationary contact 52 mounted on the circuit breaker panel 11 and a lower terminal connection 53 also mounted thereon.

10 The movable contact structure of field switch 51 includes a contact 50 mounted on a contact carrying arm 55. The contact carrying arm is connected by the lead 54 to the lower terminal 53. The contact arm 55 is pivotally mounted at 56 and is urged to a position wherein the contact surface 50 is in engagement with the stationary contact 52 by the tension spring 57 which engages the arm 55 of arm 55.

15 Another arm 60 mounted on the movable contact carrying arm 55 is pivotally connected at 61 to the operating link 62. The opposite end of operating link 62 is provided with a slot 63 which engages a stud 64 on the circuit breaker operating structure. When the movable contact surface 50 is in engagement with the stationary contact 52 of the field switch 51, then a by-pass circuit through resistance 85 exists from the field winding 40 along conductor 71 to stud 72, thence along conductor 73 to the stud or contact 74; then over the stationary lower disconnect contact 75 of the field switch to the movable disconnect contact 76 mounted on the back connection stud 77 of the circuit breaker panel; then to the contact 53 carried by the back connection stud 77, then through the lead 54 to the contact carrying arm 55 to the contact surface 50 thereof, then through the stationary field switch contact 52 mounted on the back connection stud 80 to the movable disconnect contact 81 in engagement with the stationary disconnect contact 82 to the contact stud 83, thence over conductor 84, through the resistance 85, over conductors 86 and 87 to the winding 40.

20 As has heretofore been pointed out, the link 62 interconnects the field switch contact carrying arm with the operating elements of the circuit breaker 13 so that the stud 64, when the circuit breaker is closed, engages the lower end of slot 63 to draw the link 62 in a counterclockwise direction (with respect to Figure 4) to cause 25 the contact arm 55 also to rotate counterclockwise to disengage contacts 50 and 52 of the field switch.

25 When the operating members 17 of the circuit breaker 13 are moved to the open circuit position, as shown in Figure 5, then the stud 64 thereon moves upwardly, thus permitting the link 62 to move upwardly. The relaxation of the downward force exerted by the stud 64 on the slot 63 of the link 62 now permits the tension spring 51 of the field switch contact arm 55 to cause the field switch contact arm to rotate to closed circuit position.

30 It should here be noted that reliance is not placed on the movement of the operating arm 17 upwardly when the circuit breaker is open to force the link 62 upwardly to close the field switch, but rather slot 63 is of sufficient length so that the spring 51 will be able to rotate the contact 50 of the field switch to closed circuit position before the circuit breaker is entirely open.

35 The slot may be made of sufficient length, in fact, so that the field switch is permitted to close 40 at the moment that the circuit breaker movable

contact begins to open but before the contacts actually separate.

The slot 63 and stud 64 are so arranged with respect to the circuit breaker tripping operation that on the instant when collapse occurs of the linkage mechanism 19, as described above, and the arm 17 starts on its upward clockwise movement about its pivot 18, the pin 64 on the arm 17 moves a distance from the lower surface of the slot 63 sufficient to permit the spring 57 to rock the contacting arm 55 clockwise about its pivot 56 into engagement with the stationary contacts 52 and 53 before the movable contacts of the switch 16 have disengaged their stationary contacts 30 and 31.

That is to say, upon the tripping operation being initiated, the first movement which occurs in the toggle mechanisms including 17 and the movement of the link 62 permits a closing operation of the switch contact 50 against the stationary contact before the toggle movement has progressed sufficiently far to disengage the contact 16 from its stationary contacts.

My invention also provides for an auxiliary field switch 151 which may be operated to connect the resistance 85 across the winding 40 when the circuit breaker and field switch operating elements are entirely withdrawn from the switchboard cell.

This ensures that the resistance 85 is in parallel with the field windings 40 both during closing and opening operations, however these are to be effected.

For this purpose, I provide a movable bridging contact 150 on my auxiliary field switch 151, the said contact being mounted in the stationary portion of the switchboard structure and being arranged for operative engagement with the contact members 83 and 74.

The movable contact bridging element 150 is mounted on the contact arm 155 which is pivoted at 156 and is urged into closed contact position by the compression spring 151. When the circuit breaker and field switch operating structure is removed from the switch board cell, then spring 157 urges the movable contact 150 into bridging engagement with the contacts 74 and 83 and thus places the resistance 85 across the winding 40, the circuit being from winding 40 over conductor 71 to the stud 72, thence over conductor 73 to the contact 74, over bridging contact 150 to contact 83, then over conductor 84 through resistance 85 and conductors 86 and 87 to the winding 40.

A rod 160 is carried by the circuit breaker panel in the manner hereinafter shown and is so arranged that when the circuit breaker truck is in operative position within the switchboard cell, as shown in Figures 4 and 5, the rod 160 engages the contact bridging element 150 to move it out of engagement with the contacts 74 and 83.

Accordingly, when the circuit breaker truck is in operative position, only the principal field switch 51 is operative to connect or disconnect the resistance 85 across coil 40. When the circuit breaker truck is racked out of position, then the rod 160 is withdrawn from its engagement with the movable bridging contact 150 of the auxiliary field switch 151, and the spring 157 thereof can now urge the contact 150 into bridging engagement with contacts 74 and 83, closing the circuit in the manner above set forth. The operation and utility of the auxiliary field switch will be hereinafter set forth.

From the foregoing, it may therefore be seen

that the circuit breaker and field switch elements are so arranged that when the circuit breaker truck is in operative position in the switchboard structure, then:

- 5 1. The field switch 51 and the auxiliary field switch 151 will be opened when the circuit breaker contacts are closed; and
- 10 2. When the circuit breaker contacts are open, the field switch 51 will close, thus connecting resistance 85 across the coil 40.
- 15 3. When the circuit breaker truck is removed from the cell, then auxiliary field switch 151 is closed, for purposes hereinafter set forth.
- 20 4. As is hereinafter set forth, the movable contact 16 of the circuit breaker is intended to open before the circuit breaker is racked out of position. Inasmuch as switch contacts 50 and 52 are closed when the contacts of switch 16 are opened before racking out operations begin, the auxiliary field switch 151 is opened.

As the circuit breaker is racked out of position, the removal of rod 160 permits auxiliary field switch 151 to close. The disconnect contacts 81-82 and 76-75 are so arranged that the auxiliary field switch 151 may close before these contacts are disconnected so that resistance 85 will always be across winding 40 when the circuit breaker is intended to be open.

By this means a simple automatic method is provided for placing a resistance across the field winding of a motor or dynamo immediately upon the opening of the circuit to prevent damage owing to a momentary rise in voltage.

Since this operation is automatic and requires no separate manual manipulation, the safety factor is greatly increased. Just preceding the opening of the circuit for any cause, the resistance is automatically placed across the field winding. This is so whether the circuit breaker is opened automatically or manually. Should there be any attempt to rack out the circuit breaker, then, in addition to the means which are provided to automatically trip the circuit breaker open, an auxiliary field switch is provided to place the resistance across the field winding.

The primary purpose of the auxiliary switch 151 is to ensure that where the resistance 85 is utilized in connection with a number of circuit interrupters, this resistance will be in circuit to protect the field winding even though one or more of the circuit breakers may be withdrawn from its cell.

Thus, where one or more supply circuits are utilized on the same load system, each of the lines having its own circuit breaker, and where a single resistance 85 is used to protect the field winding of the load or motor; then, upon the withdrawal of one of the circuit breakers from its cell while the others remain connected, it is important that the resistance 85 nevertheless be arranged to be connected across the field upon the opening of the other circuit breakers.

Accordingly, auxiliary field switch 151, which closes upon removal of the circuit breaker from its cell, produces this result.

This will be obvious from an examination of Figure 7 (where a slightly different auxiliary field switch 451 is shown which, however, functions in the same manner as auxiliary field switch 151 of Figures 1 to 3).

In Figure 7, all of the elements mounted on the circuit breaker trucks 10^a and 10^b are the same as the elements mounted on the circuit breaker truck 10 of Figures 1 to 3. The sole exception

is that the disconnect contacts 401, 402, 403 and 404 of the field switch 51 are sliding contacts which remain in engagement with each other over a substantially greater movement than obtains with the type of disconnect contacts utilized for the circuit breaker terminals. This will ensure that the field switch 51 will be operative to connect the resistance across the winding 40 until the auxiliary field switch 451 is closed. The auxiliary field switch has a different mechanical form (hereinafter described) than auxiliary field switch 151 of Figures 1 to 3; but operates in substantially the same manner and has an identical function. It bridges the terminals 83 and 74 when the circuit breaker truck is withdrawn from the cell.

The circuit breakers here shown are two pole circuit breakers having bridging contacts 16 and 16^a which are mechanically interlocked by the member 274 to operate together.

Generator 410 is connected through the circuit breaker mounted in truck 10^a to energize the field winding 40 as follows: current flows from the generator along conductor 8 to the closed bridging contact 16, then to conductor 71; then through conductor 411 to the field winding 40 and through conductors 87 and 9 to the closed bridging contact 16^a, then through conductor 413 to the generator.

The current from generator 410^a also may flow through field winding 40, when the circuit breaker in truck 10^b is connected and closed, over an exactly similar path.

Resistance 85 is connected across the winding 40 as follows: the connection is made from the left end of resistance 85 through conductor 84 to the contact stud 83, then through the field switch 51^a or auxiliary field switch 451 (when either of these switches are closed) to the contact stud 74, then through conductor 73 to the contact stud 72, then through conductors 71 and 411 to the field winding; through the field winding to conductors 87, 9^a and 415 to the contact stud 74^a, then through the field switch 51^b or auxiliary field switch 451^a (when either of these switches are closed) to the conductor 86 to the right end of resistance 85.

It will thus be seen that the field switches are in series; so that both must be closed to connect the resistance 85 across the winding 40.

When the circuit breakers in trucks 10^a and 10^b are both racked in and in closed position, then current from both generators 410 and 410^a energizes the winding 40.

Should a fault occur in the line circuit from, say, generator 410^a then the breaker in truck 10^b will be opened, thus closing the field switch 51^b in the manner previously described (should the breaker in truck 10^a also open, it may be re-closed). The closing of field switch 51^b thus leaves the by-pass circuit through the resistance 85 in such condition that it may be closed by closing of field switch 51^a should the circuit breaker in truck 10^a then be tripped.

Should a fault occur in the load circuit, then both circuit breakers will be tripped and both field switches 51 will be closed thus connecting the resistance 85 across the winding.

When it is desired to rack out truck 10^b, while at the same time it is necessary to operate the motor 41 from the generator 410, then, the auxiliary field switch 451^a will bridge the contact studs 83^a and 74^a, thus leaving the by-pass circuit in such condition that the closing of field switch 51^a (in truck 10^a), upon the tripping of its

circuit breaker, will establish the by-pass circuit through the resistance 85.

Thus, by the use of the auxiliary field switch 151 (of Figures 1 to 3) or 451 (of Figure 7), the removal of one of the circuit breakers from its cell will nevertheless permit the resistance 85 to protect the field winding upon the tripping of the remaining circuit breakers.

While this system has been described in connection with two circuit breakers, it is clear that, with simple variations which should now be obvious, it may be utilized with three or more circuit breakers. It is also obvious that, while two pole circuit breakers have here been shown, the system may, with obvious adaptations, be utilized with any single pole or multi-pole circuit breakers.

One physical embodiment which my invention may take is shown in Figures 1 to 3.

In Figure 1, I have shown a circuit breaker truck 10 mounted on wheels 201, 202 and racked out of the stationary switchboard cell 20. The side enclosing sheets of each of these members have been removed in order to show the operating elements.

The cell 20 comprises a framework which includes upper and lower structural members 211 and 212 on each side of the cell and vertical structural members 213, 214, 215 and 216. This framework is covered on top, bottom and sides by suitable enclosing sheets. The front of the cell 20 is closed by the front panel 217 of the circuit breaker truck. The rear of the cell 20 is closed by the removable flanged panel 218.

A panel 220 of insulating material is mounted between the vertical members 215 and supports the male stationary disconnect contacts 37 and 38 of the circuit breaker. These members extend through the panel 220 and are provided with terminals 221 and 222 for connection to an electrical circuit, which in the present instance is intended to be the field winding 40 of the motor 41 or any other similar inductive circuit.

The stationary male disconnect contacts 82 and 75 of the field switch are also mounted on the panel 220. The terminals of these contacts extend through the panel 220 and form respectively the contact studs 83 and 74 (see Figures 1 and 3).

Leads 84 and 73 are connected thereto to complete the resistance circuit in the manner which has already been set forth.

The contact member 83 may comprise a suitable plate of conductive material secured to the back of the panel 220, as shown particularly in Figure 3, in conductive relation with the field switch stationary disconnect contact member 82.

The member 82 may be secured by the bolt 231 to the angle member 230, which, in turn, is secured by the bolt 232 to the panel 220. A bolt 234 passing through the angle member 230, and the panel 220 may engage the plate 83, thus firmly securing it to the panel 220 and ensuring the conductive relation between the disconnect contact 82 and the contact plate 83.

The lead 84 may be connected to the contact plate 83 by a bolt 235 or in any other suitable manner.

The contact stud 74 is secured to the back of the panel 220 by being mounted on a back extension of the stationary field switch disconnect contact 75.

It is also securely supported in position by the switch brackets 240 of the auxiliary field switch operating arm hereinafter described.

The stationary disconnect contact 75 is secured by a bolt 241 to the angle member 242 which is secured by the bolt 243 to the front of the panel. Bolt 244 passes through the angle member 242 and the panel 220 and terminates in a stud 245 to which the lead 73 may be connected.

In this manner the stationary disconnect contact 75 and the contact plate 74 may each be connected through the angle member 242 and the bolt 244 to the lead 73.

The circuit breaker truck 16 (Figure 1) carries the circuit breaker panel 11. The back connection studs 32 and 33 of the circuit breaker are mounted on this panel to project beyond the back thereof. Stationary contact members 31 and 30 (Figure 4) of the circuit breaker are mounted on the projections of these studs beyond the front of the panel 11 to engage with the movable bridging contact 16. The stationary contacts 30 and 31 are not shown in Figures 1, 2 and 3 but are schematically indicated in Figures 4 to 6. These, of course, may take any conventional form which will enable them to cooperate with the bridging contact 16.

The back connection studs 32 and 33 terminate in movable disconnect contact elements 35 and 36 (Figure 1) which, when the circuit breaker is racked into position, engage with the male stationary disconnect contact elements 37 and 38, as previously described in connection with the schematic figures.

The field switch 51 (Figures 1, 2 and especially 3) comprises a contact carrying arm 55 which is mounted on the pivotal member 56 which, in turn, is supported by suitable brackets 250, 251 (Figure 2) on the panel 11 of the circuit breaker. Contact carrying arm 55 carries a contact member 50 having a contacting face which is engageable with an upper stationary contact 52 and an arcing contact 260.

Upper stationary contact 52 is mounted on and operatively connected to the back connection stud 80, to which is secured the movable disconnect contact member 81.

A lead 56 connects the contact member 50 to the lower terminal 53 of the field switch, which, in turn, is secured in any suitable manner to the front end of back connection stud 77 on the back end of which is mounted the movable disconnect contact 76.

The back connection studs 80 and 77 are spaced by the insulating member 262 on which is mounted the rod 160.

The field switch 51 has a magnetic blow-out coil 263, one terminal of which is connected to the back connection stud 80, the other terminal of which is connected to the plate 264 to which the arcing horn 265 is secured. The arcing horn carries arcing contact 260.

An arc quencher 266 may be mounted in any suitable manner over the movable contacts 50-52-260 of the field switch.

Contact carrying arm 55 of the field switch has an extension 58 to which is secured one end of the tension spring 57, the other end being secured at 270 to the circuit breaker panel 11. The spring 57 tends to rotate the contact carrying arm 55 in a clockwise direction to bias the switch toward a closing position.

An arm 60 on the contact carrying arm 55 is pivoted at 61 to the operating link 62. The opposite end of the link has a slot 63 therein which is in operative engagement with the stud

64. Stud 64 is mounted on a U-shaped bracket 272 (Figure 2) which is secured by bolts 273, 273 to the insulated bar 274 which interconnects the two poles 275, 276 of the two-pole circuit breaker here shown for simultaneous operation; that is, operating elements which are connected to the members of pole 275 to operate the same will cause the elements of pole 276 simultaneously to operate by reason of their being united by the insulating bar 274.

The circuit breaker operating members 17 are so arranged that the stud 64 will move downwardly in a counter-clockwise position around the pivot 18 when the movable circuit breaker contact 16 is moved to closed circuit position.

As will now be clear, when the toggle 17 collapses on its first movement, the lug 64 is carried away from engagement with the bottom of the slot 63. This is immediately sufficient to rock the field switch 51 under the action of its spring 57 in a clockwise direction about its pivot 56 to engage its stationary contacts 52 and 53—this occurring before any opening of the main circuit breaker 13.

As the toggle's action continues thereafter, the main circuit breaker 13 disengages its contacts moving to an open position and during this operation the lug 64 has moved to its position at which it engages the upper inner surface of the slot 63 as shown in Figure 3, the toggle then being in its completely collapsed position.

As the toggle mechanism 17 is operated in a counter-clockwise direction about its pivot 18, the lug 64 moves in the slot 63, and thus there is no effect during this first portion of the movement of the main switch. The closing operation of the main switch 13, therefore, continues to a point just before its contacts are engaged. At this point, lug 64 engages the lower surface of slot 70.

As the last final locking operation on the main circuit breaker occurs, the lug 64, in engagement now with the lower surface of slot 70, will exert a pull on the link 72 which acts through the pin 61 to rock the bell crank shaped field switch arm 55 about its pivot 56 in a counterclockwise direction to disengage its contacts.

Thus, operation of the field switch 51 occurs to reclose its contacts before the main circuit breaker is opened to separate these contacts just after the main circuit breaker is closed—this being effected by the free play provided for the lug 64 in the slot 63.

The closing operation may either be performed manually or by means of a solenoid operated closing device 281 (Figure 1) which, by the link 282, is connected to the operating members 17.

A shunt trip 284 may also be provided for the circuit breaker connected by a link 285 to the latch 23.

The slot 63, therefore, ensures that the field switch will not open until the circuit breaker contacts are closed, while the field switch will close just before the circuit breaker contacts are fully separated during their opening movement.

The field switch 51 operates, as previously set forth in connection with the description of Figures 4 and 5, when the circuit breaker is in position in the switchboard cell.

When it is desired to rack the circuit breaker out of the switchboard, then auxiliary field switch 151 becomes operative. The circuit breaker panel 11 carries a tripping arm 396 which is engageable with the roller 301 on one of the side sheets of the cell structure 20 (see Figure 1). The arm

300 has a chamfered surface 302—303 communicating with the notch 304.

When the circuit breaker is in position in the cell, the roller 301 in the cell engages the notch 304. As the racking out operation commences, the movement of the circuit breaker truck, which moves the arm 300 past the roller 301, will cause the arm 300 to rotate in a counterclockwise direction with respect to Figure 1 around its pivot 305 as the roller 301 enters the chamfered surface 303. This will cause the link 306 to be moved downwardly, thus tripping the latch in the same manner as does link 285 when the shunt trip 284 is operated.

Thus, in the event that the circuit breaker has not been opened before it is racked out, it is tripped open on the initiation of the racking out operation. The engagement of roller 301 with surfaces 302 and 303 of arm 300 also serves to trip the circuit breaker open, should it be racked into position while closed.

The racking operation herein set forth is shown in Patent No. 2,237,367, assigned to the assignee of the present application.

Simultaneously, with the racking out of the circuit breaker, rod 160 is moved out of engagement with the end of the plunger 310. Plunger 310 is mounted in the panel 220 (see particularly Figures 1 and 3) and is urged into movement toward the left by the compression spring 311. The end of plunger 310 is in engagement with the adjustment nut 312 on the end of rod 160. The rear end of the plunger 310 carries a member 314, which is engageable with the plate 315, on the operating arm 155 of the auxiliary field switch 151.

The operating arm 155 is pivoted at 156 on the brackets 240 on the rear of the panel 220 and is urged in a counterclockwise direction by the compression spring 157 which is mounted at one end in the panel 220 and at the other end bears against a pin 320 on the arm 155.

When the circuit breaker truck 10 is in position in the cell, the rod 160 engages the plunger 310 to push its member 314 against the plate 315 to rotate the arm 155 in clockwise position so that the contact 150 is out of engagement with the stationary contact members 83 and 74.

As the circuit breaker is racked out of position, the rod 160 is withdrawn, thus permitting the compression spring 311 to move the plunger 310 to the left, thereby permitting compression spring 157 to rotate the contact carrying arm 155 in counterclockwise direction.

This permits the bridging contact 150 to close on the stationary contacts 83—74, again connecting the resistance 85 across the field winding 40.

In Figure 8, I have shown a modified form of auxiliary field switch 451 which corresponds in function to the above described auxiliary field switch 151, and which already has been mentioned in connection with the description of the schematic diagram of Figure 7.

In Figure 8, the circuit breaker operates in the same manner as the circuit breaker of Figures 1 to 3 and the field switch 51^a is identical with the field switch 51 of those figures. All other parts of the circuit breaker structure and its truck are identical with the parts previously described. The differences lie in the modified form of auxiliary field switch 451 and its associated parts.

The back connection studs 80^a and 77^a of the field switch pass through openings in the panel 11 and through corresponding openings in the flanges 420 and 421 of the T-shaped insulating

member 422 when their ends are secured by suitable metallic washers and bolts 424. Metallic current conducting members 426 are secured against opposite surfaces of the insulating member 422 by the bolts 424 and by any other suitable means of securement as, for instance, the screws 425.

The ends of the conductors 426 are bent to form retaining flanges 427.

A spring metal conductor 430 (on each side) is secured at 431 in the end of the insulating supporting member 422; the opposite end of each conductor 430 is urged by spring 432 away from the support 422 so that the contacting faces 435 may have suitable pressure to make a good sliding contact with the disconnect contact members 440, 440. The free ends of the members 430 are restrained in their outward movement in response to the springs 432 by the retaining flanges 427. A current carrying connection between conductors 426 and contacts 430 is made by the pig-tails 442, each secured at one end by the screws 425 and at the opposite end to the bolts 444 which guide and secure the springs 432.

The upper contact 430 is thus electrically connected to the upper connection stud 80^a; and the lower contact 430 is connected to the lower stud 77^a.

The disconnect contacts 440 are each secured on suitable insulating supports 460 which extend from the insulating panel 461 mounted on the rear wall member 220 of the cell. The bolts 465, which secure the insulating panel 461 to the insulating panel or wall member 220, also electrically connect the ends of disconnect contacts 440 to their respective contact studs 83^a and 74^a.

The auxiliary field switch 451 is a bridging member adapted to bridge contacts 83^a and 74^a. Member 451 is mounted on the end of plunger 470 which passes through the opening 471 in the panel 220 and opening 472 in panel 461.

Opening 471 is provided with an inner annular ledge 473 against which one end of a compression spring 475 bears.

The opposite end of the spring bears against the end of a sleeve 477 mounted on the plunger 470.

The spring 475 thus biases the contact member 451 toward engagement with contacts 83^a and 74^a.

When the circuit breaker is racked into position, the end of member 422 bears against the end of plunger 470 and forces the contact 451 out of engagement with the contacts 83^a and 74^a. When the circuit breaker is racked out, then the spring 475 is free to urge the contact member 451 into closed position thus closing the auxiliary field switch.

The length of the disconnect contacts 440 is such as to ensure that the field switch 51^a will be connected in circuit with the resistance 85 and the field winding during the racking out process at least until the auxiliary field switch 451 is closed.

In the foregoing, I have set forth a field switch coupled with an auxiliary field switch for connecting a resistance across the field winding of a dynamo, or in a similar inductive circuit, to protect the device against momentary rise in voltage which may occur on the breaking of the circuit.

The operation of each of the elements has been described particularly in connection with schematic Figures 4 to 6 and also in connection with the description of the individual elements of the apparatus of my invention.

Generally, the device is so arranged that when the circuit breaker opens, the field switch closes, thus connecting a resistance across the field winding. After the circuit breaker is closed, the field switch is automatically opened. The field switch and the circuit breaker are so arranged that the field switch opens after the circuit breaker is closed and so that the field switch closes before the circuit breaker is fully opened.

An auxiliary field switch is provided and is automatically operable to closed position when the circuit breaker is racked out of the switchboard cell.

All of the operations connected with the switching of a resistance in circuit across the winding of the field coil are automatic so that no additional operations, manual or otherwise, need be performed, and the equipment, as well as the operator, is fully protected.

In the foregoing, I have set forth in schematic form and in preferred embodiments various elements of my invention. Many variations and adaptations thereof should now be obvious to those skilled in the art. I, therefore, prefer to be bound not by the specific disclosure herein but only by the appended claims.

I claim:

1. A circuit breaker, a panel for carrying the same, a cell for said circuit breaker, said cell having a wall; said panel being movable toward and away from said wall; said wall carrying a switching member; means on said panel engageable with said switching member to open the same when the panel is in one position with respect to said wall and disengageable from said member to close the same when said panel is in another position; a switching member on said panel in parallel with said switching member on said wall; said switching member on said panel being closed when said circuit breaker is open; and disconnect contacts between said two switching members establishing the parallel connection therebetween.

2. A circuit breaker, a panel for carrying the same, a cell for said circuit breaker, said cell having a back wall; said panel being movable toward and away from said back wall; said back wall carrying a switching member; means on said panel engageable with said switching member to open the same when the panel is in one position with respect to said back wall and dis-

engageable from said member to close the same when said panel is in another position; a switching member on said panel in parallel with said switching member on said back wall; said switching member on said panel being closed when said circuit breaker is open; and disconnect contacts between said two switching members establishing the parallel connection therebetween; said disconnect contacts being slideable contact members.

3. A circuit breaker, a panel for carrying the same, a cell for said circuit breaker, said cell having a back wall; said panel being movable toward and away from said back wall; said back wall carrying a switching member; a plunger on said panel engageable with said switching member to open the same when the panel is in one position with respect to said back wall and disengageable from said member to close the same when said panel is in another position; a switching member on said panel in parallel with said switching member on said back wall; said switching member on said panel being closed when said circuit breaker is open; and disconnect contacts between said two switching members establishing the parallel connection therebetween, said disconnect contacts maintaining current carrying engagement during outward movement of said panel until said plunger is completely disengaged from the switch in the cell.

4. A circuit breaker, a panel for carrying the same, a cell for said circuit breaker, said cell having a back wall; said panel being movable toward and away from said back wall; said back wall carrying a switching member; a plunger on said panel engageable with said switching member to open the same when the panel is in one position with respect to said back wall and disengageable from said member to close the same when said panel is in another position; a switching member on said panel in parallel with said switching member on said back wall; said switching member on said panel being closed when said circuit breaker is open; and disconnect contacts between said two switching members establishing the parallel connection therebetween; an insulating support on said panel for the elements of the disconnect contacts carried thereby; said plunger being carried by said insulating support.

WALTER HAINES SCHYMIK.
